ELECTROLYTIC CELL.

1,278,724.

Specification of Letters Patent. Patented Sept. 10, 1918.

Application filed March 28, 1917. Serial No. 157,879.

To all whom it may concern:

Be it known that I, FRANK H. NICKLE, a citizen of the United States, and residing at Saginaw, in the county of Saginaw and State of Michigan, have invented a new and Improved Electrolytic Cell, of which the following is a specification.

This invention relates to electrolytic cells of the diaphragm type, and especially to such as are adapted for the electrolysis of alkali chlorid for the production of caustic alkali and chlorin.

The primary object of my invention is to provide a simplified type of cell that is adaptable to suspension from over-head members, thereby eliminating the usual supporting base, securing better electrical insulation, more effective air cooling, and less expensive construction.

Another object is to provide means to support the anode cover, and the anodes depending therefrom, independently of the electrolyte vessel, so that the anode supporting cover may be readily adjusted to any desirable elevation, or may be lifted out of the vessel without the loosening of bolts or clamping members.

Figure 1 is a plan view of a cell in which my invention is embodied. Fig. 2 is a corresponding side elevation with parts broken away to show the interior construction. Fig. 3 is a cross-section on line 3—3 of Fig. 2.

In the embodiment of my invention, the vertical members 1, shown broken off in Fig. 3, serve as supports, and resting thereon is a cross-bar 2 at each end of the cell. Below each cross-bar is a centrally disposed vertical U-shaped plate, 3, which serve as an end for the electrolyte vessel. A permeable diaphragm, 4, inclosed by and in contact with a perforated sheet metal cathode 5 is made to conform to the U-shaped end walls, thereby forming the side walls and bottom of the vessel. Conforming to the U-shaped cathode-diaphragm is a sheet metal container 6, which is spaced apart at the ends by the separator 7, thereby forming a compartment for the cathode products.

At each end of the cell is a U-bolt 8, the upper ends of which are provided with nuts 9, which bear on the cross-bar 2. When the U-bolt 8 is tensioned the cathode-diaphragm, separator and container are all simultaneously clamped together about the U-shaped end wall of the electrolyte vessel which serves as a compression member. The upper

edges of the cathode-diaphragm and container are reinforced and held in alinement by means of the horizontal strips 10 and 11.

The feed cup 12, which may be of any desired form and is either independent of or an integral part of one of the electrolyte vessel end walls, is supplied with brine from the pipe 13. Communicating between the feed cup and the vessel is a passage 14 through which the electrolyte is replenished.

Centrally disposed, and supported upon the cross-bars 2, is a member 16, from which the anode cover 17 is suspended by tension rods 18 having nuts whereby the elevation of the ends of the cover plate may be independently adjusted. Depending from the anode cover 17 is a plurality of anodes 19, the upper ends of which protrude up through the anode cover and receive the positive electrical connection 20.

Chlorin gas may be withdrawn from the vessel through the outlet 21 in the anode cover. The joint, between the anode cover and the members 3 and 11, may be sealed with any plastic means 22 that will readily permit the raising or lowering of the anode cover. The hydrogen liberated in the cathode compartment may be withdrawn through any suitable opening (not shown) in the cell container. The caustic soda, or liquid cathode products may be withdrawn by pipe 23, thereby, if desirable, avoiding submergence of the cathode. When the cathode is maintained un-submerged it is evident that, since the atmospheric air is excluded from the chamber around the cathode, any hydrogen which collects therein may be withdrawn through the pipe 23, thus providing a commercial source for this element. Further, the exclusion of air from contact with the catholyte, which drains through the cathode perforations, prevents secondary reactions which form carbonates and tend to clog up the cathode perforations and render the diaphragm less permeable.

In the usual diaphragm cell construction, the weight of the anodes is carried by the cell container, the electrolyte vessel or by means within the vessel. These various supporting means serve as compression members in transmitting the weight of the anodes downward to the cell base. In the presence of moisture, or in contact with liquids, these supporting means become more or less electrical conductors, hence it is obvious that it is desirable to suspend and insulate the

anode supporting cover as free from the other elements of the cell as possible. To attain this, suitable insulation 24 may be placed between the anode cover and the cross-bars 2.

Leakage of solutions from the cell, due to imperfect joints and disintegration of the materials of construction, have a tendency to keep the base and the supports of the usual cell saturated, the result being loss of current from the cell to the source of supply. This current loss is easily avoided in a cell of the suspension type, such as I have illustrated and described, by inserting suitable insulation 25 between the supporting members 1 and the cross-bar 2. This insulation and the cross-bars, being well above the level of the liquor within the cell, it is evident that the effectiveness to prevent current loss, may be maintained indefinitely regardless of any leakage that may saturate the lower extremities of the cell container.

The anode supporting cover being supported substantially free from the walls of the electrolyte vessel, it is evident that the same may be lowered to any desirable elevation, thereby increasing the immersion of the anodes in the electrolyte so that the entire length below the anode cover may become effective.

In the cell illustrated, the cathode-diaphragm recedes away from the upper face of the anodes, thereby making the shortest electrical path between the electrodes at the lower end of the anodes. As the disintegration of the anodes is most active where the greatest amount of current leaves the face of the anodes, it is evident that the anodes will progressively disintegrate from the bottom upward, which tends to increase the life of the anodes.

In my suspension type of cell, the absence of a supporting base proves advantageous from the standpoint of heat radiation, as it renders the bottom of the container, as well as the sides, effective cooling surface, thereby permitting higher current densities and increasing the output of the cell.

It is clear that many changes may be made in the details of construction without departing from the spirit of my invention. I do not, therefore, wish to be limited otherwise than as indicated by the subjoined claims.

55 I claim:—

1. An electrolytic cell comprising a trough shaped container for electrolyte, a trough shaped cathode depending into the container and spaced therefrom, a cover for the space between the upper edges of the cathode, anodes carried by the cover and depending into the container within the confines of the cathode, and means for suspending the cover substantially free from the cathode.

2. An electrolytic cell comprising a U-shaped container for electrolyte, said container having end walls, a cathode within the container, said cathode being U-shaped in cross section and extending across between the end walls of the container, a cover for the space between the edge portions of the cathode and the end walls of the container, anodes depending from said cover, and means for suspending the cover substantially independently from the cathode and the container. 70

3. An electrolytic cell comprising a U-shaped container for electrolyte, said container having end walls, a cathode within the container, said cathode being U-shaped in cross section and extending across between the end walls of the container, a cover for the space between the edge portions of the cathode and the end walls of the container, said cover projecting below the upper edges of the cathode, means for sealing the joints between the cover and the cathode and between the cover and the end walls of the container, anodes depending from the cover, and means for suspending the cover independently from the cathode and the container. 75

4. In an electrolytic cell, a container, a vessel having U-shaped end walls for the container, a continuous permeable cathode-diaphragm forming the sides and bottom of the vessel, said vessel being adapted for electrolyte, means for supporting said container, said means comprising overhead cross-arms coöperating therewith. 80

5. In an electrolytic cell, a container, a cathode-diaphragm within the container, said cathode-diaphragm being arranged to divide the container into anode and cathode compartments for the electrolyte, overhead means for supporting the container, said means comprising tension members in engagement with members adapted to withstand bending moment. 85

6. An electrolytic cell having a container, an anode and a cathode compartment within the container, a cover for the anode compartment, anodes depending from the cover, and overhead means adapted to suspend the container and the cover. 90

7. An electrolytic cell having a container, a permeable cathode-diaphragm dividing the container into anode and cathode compartments, a cover for the anode compartment, anodes depending from the cover, said cover being suspended independently of and at an elevation lower than the upper marginal edge of the cathode-diaphragm. 95

8. In an electrolytic cell, an electrolyte vessel substantially rectangular in horizontal cross-section and having end walls, transverse cross-bars mounted on the end walls and projecting therefrom, a container surrounding the electrolyte vessel and spaced 100

130

- therefrom to form a cathode compartment, and means for hanging the container on the said cross-arms.
9. An electrolytic cell having a container, a vessel within the container, said vessel being adapted for electrolyte, a cover for the vessel, anodes depending from the cover into the electrolyte, and means for suspending the cell-container and cover from overhead members.
10. An electrolytic cell having a vessel adapted for electrolyte, a cover for the vessel, anodes depending from the cover into the electrolyte, means for supporting the said cover free from contact with the electrolyte, said means consisting of tension rods in engagement with a member adapted to withstand bending moment.
11. An electrolytic cell having a container, a cathode-diaphragm within the container, said cathode-diaphragm forming the sides and bottom of an anode vessel, a cover for the vessel, anodes depending from the cover, said anode cover being suspended independently of and at an elevation lower than the upper edge of the vessel, thus permitting the anodes to be immersed in the electrolyte throughout their length below the cover.
12. An electrolytic cell including a liquid-tight container for electrolyte, means for supporting the container from above, said means including means for electrically insulating the cell.
13. An electrolytic cell including a liquid-tight container for the electrolyte, means for supporting said container, an anode carrier, anodes supported on said carrier depending into the electrolyte, and means for supporting said carrier from above and for insulating said supporting means from the means for supporting the container.
14. In an electrolytic cell, the combination of a vessel containing electrolyte, a cover for the vessel, anodes depending from the cover into the electrolyte, said cover being suspended independently of the vessel and out of contact with the electrolyte therein.
15. In an electrolytic cell, an electrolyte vessel substantially rectangular in horizontal cross-section and having U-shaped end walls, transverse cross-bars mounted on the end walls and projecting to engage supporting means, said supporting means consisting of vertical members independent of the cell.
16. An electrolytic cell comprising a substantially trough shaped container for electrolyte, U-bolts passing around the container at the ends thereof, cell-supporting cross-bars extending transversely of the cell at the upper sides thereof and cooperating with the upper ends of the U-bolts to support the container from above, anodes depending into the container, and means extending across between the cross-bars for supporting the anodes from above.
17. In an electrolytic cell, a cathode-diaphragm forming the side walls of a vessel, electrolyte within the vessel, a cover for the vessel, anodes depending from the cover into the electrolyte, means for suspending the cover independently of the vessel and out of contact with the electrolyte therein, said means consisting of overhead members.
18. An electrolytic cell comprising a trough-shaped container having its end walls formed in a plurality of sections, the sections of one of the walls being disposed in the same vertical plane, and a sheet-like cathode-diaphragm extending longitudinally of the container to separate it into two compartments, the end of the diaphragm being interposed between the sections of the wall.
19. In an electrolytic cell, the combination of a pair of supporting arms, U-shaped end walls suspended under the arms, a cathode-diaphragm conforming to the end walls and clamped thereto to form a trough-like vessel, electrolyte within the vessel, a cover for the vessel, a container in which liquid that passes through the cathode-diaphragm is received, anodes depending from the cover into the electrolyte, means for suspending the cover independently of the vessel and out of contact with the electrolyte therein, said means consisting of a longitudinal bar mounted upon the said supporting arms.
20. An electrolytic cell comprising a trough-shaped container having end walls, a cathode extending longitudinally of the container, said cathode also being trough-shaped in cross-section, the end walls of the container including an inner and an outer member both arranged in the same vertical plane, the ends of the cathode being received between the inner and outer members of the corresponding end wall, and means for clamping the members together upon the cathode.
21. In electrolytic apparatus, a container, a permeable diaphragm dividing the container into anode and cathode compartments, electrolyte within the anode compartment and an anode element immersed therein, a perforated metal cathode element surrounding the diaphragm and adjacent thereto on the side thereof most remote from the anode; an outlet for the cathode, and means for suspending the anode element, cathode element and the container, said means comprising tension members co-operating with overhead cross arms.
22. In a diaphragm cell, the combination of an electrolyte vessel having end walls, a permeable cathode-diaphragm U-shaped in cross section extending across between the

end walls, said end walls and cathode-diaphragm forming a vessel adapted for the electrolyte undergoing decomposition, a container surrounding the cathode-diaphragm and spaced therefrom by means of 5 U-shaped separators to form a compartment adapted for receiving the liquid and gaseous cathode products, and means for withdrawing the said cathode products, said means 10 comprising an outlet in the container at an elevation below the lower extremity of the electrolyte vessel.

23. In electrolytic apparatus, a permeable cathode-diaphragm element forming the 15 sides and bottom of an anolyte vessel, a cover for the anolyte vessel, an anode element immersed in the anolyte, a closed container exterior to the anolyte vessel and spaced therefrom to form a compartment 20 adapted for receiving the catholyte and hydrogen, and means for withdrawing the catholyte and hydrogen and excluding atmospheric air from the sides and bottom of the anolyte vessel to enable the recovery of 25 pure hydrogen, said means comprising an outlet in the container at an elevation below the lower extremity of the anolyte vessel.

24. In an electrolytic cell, a container 30 adapted for electrolyte and supporting the weight thereof, electrodes immersed in the electrolyte, rigid means for suspending the container and the electrodes independently of the lower extremities of the container, said means comprising cross-arms coöperating 35 with tension members in engagement with the container.

25. In electrolytic apparatus, a rigidly suspended anode element in combination with a rigidly suspended electrolyte vessel.

40 26. An electrolytic cell including a container having a longitudinally extending

container sheet substantially trough-shaped in transverse cross-section, a substantially trough-shaped cathode-diaphragm dividing the container into two compartments, end 45 wall-forming means for the container constructed and arranged to space the cathode-diaphragm from the container sheet and to receive all inward thrusts of said container sheet, tension-rods passing around the 50 outside of the container sheet at the ends and extending upwardly therefrom, and means located above the ends of the container from which the latter is entirely suspended by tension stresses only in the upwardly extending ends of the rods.

27. A rigid electrolytic cell including a container formed of a trough shaped container sheet and end wall forming means therefor, a cathode-diaphragm dividing the 60 container into an anode compartment and a cathode compartment, rods passing around the container in the planes of the end walls and clamping the sheet to the end wall forming means, whereby the container sheet is 65 relieved of stresses longitudinally of the rods, and means associated with the upper ends of said rods for suspending the container.

28. In electrolytic apparatus, a permeable 70 cathode-diaphragm element forming at least the lower part of the sides and the bottom of an anolyte vessel, an anode element immersed in the anolyte, a closed container exterior to the anolyte vessel and spaced therefrom to form a compartment adapted for receiving the catholyte and hydrogen, and a conduit leading from said compartment at a low point therein, through which hydrogen may be withdrawn and whereby atmospheric 75 air is excluded from the compartment.

FRANK H. NICKLE.
